[57] CLAIM

The ornamental design for an offset hosel for a golf club, substantially as shown and described.

DESCRIPTION

FIG. 1 is a perspective view of an offset hosel for a golf club showing my new design;

FIG. 2 is a top view thereof;

FIG. 3 is a rear view thereof;

FIGS. 4 and 5 are side elevations as seen, respectively, from the left and right of FIG. 2;

FIG. 6 is a bottom view thereof;

FIG. 7 is a front elevation thereof; and

FIG. 8 is a cross-sectional view taken along line 8—8 of FIG. 5.

A golf club head and a shaft are shown in phantom lines for illustrative purposes only.

Fig. 1.

Fig. 2.

Fig. 4.
